W. THOMAS.
CARPET.

No. 20,627.

Patented Mar. 24, 1891.

UNITED STATES PATENT OFFICE.

WALTER THOMAS, OF YONKERS, NEW YORK, ASSIGNOR TO THE ALEX. SMITH & SONS CARPET COMPANY, OF SAME PLACE.

DESIGN FOR A CARPET.

SPECIFICATION forming part of Design No. 20,627, dated March 24, 1891.

Application filed February 16, 1891. Serial No. 381,707. Term of patent 3½ years.

To all whom it may concern:

Be it known that I, WALTER THOMAS, a citizen of the United States, residing at Yonkers, Westchester county, New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet, showing my new design.

My design consists of the body A and the border B. The body A consists of sprays of flower forms scattered upon a ground resembling foliage. The border B consists of sprays of flower and leaf forms scattered upon a ground resembling foliage and of an irregular inner and outer margin.

What I claim as new, and desire to secure by Letters Patent, is—

1. The design for carpets, consisting of the body A, substantially as shown.
2. The design for carpets, consisting of the border B, substantially as shown.
3. The design for carpets, consisting of the body A and the border B, substantially as shown.

WALTER THOMAS.
